UNITED STATES PATENT OFFICE.

CHARLES EDWARD SHAPLEY, OF AUBURN, NEW YORK.

FAUCET ATTACHMENT FOR SHOWER-BATHS.

1,146,353.

Specification of Letters Patent.

Patented July 13, 1915.

Application filed July 7, 1914. Serial No. 849,427.

To all whom it may concern:

Be it known that I, CHARLES E. SHAPLEY, a citizen of the United States of America, and a resident of Auburn, in the county of 5 Cayuga, in the State of New York, have invented new and useful Improvements in Faucet Attachments for Shower-Baths, of which the following, taken in connection with the accompanying drawings, is a full, 10 clear, and exact description.

This invention relates to certain improvements in faucet attachments for shower baths adapted to be used in connection with curtainless bath tubs and involves the use 15 of an elevated spray nozzle elongated laterally and provided with a series of orifices arranged to direct the jets of water in converging lines within the area of the bath tub, the water being conducted from the 20 faucet to the spray nozzle through a suitable conduit which is clamped to said faucet.

The main object is to provide a simple and comparatively inexpensive shower bath attachment which may be easily and quickly 25 clamped to any faucet and adjusted to any angle within a limited range for directing the jets of water to the desired locality usually within the area of the bath tub.

Another object is to make the conduit in 30 sections so that the spray nozzle may be brought to different heights according to the wishes of the user.

A further object is to provide said conduits with a reservoir for perfume or 35 soluble tablets which it may be desired to mingle with the water before emerging from the spray nozzle.

Other objects and uses relating to specific 40 parts of the device will be brought out in the following description.

In the drawings Figures 1 and 2 are respectively a top plan and side elevation (partly broken away) of a bath tub and my improved shower attachment attached to the 45 faucet thereof. Fig. 3 is an enlarged detail sectional view, partly in elevation of the shower attachment, the greater portion of the pipe leading to the spray nozzle being broken away. Fig. 4 is a horizontal sectional view, partly in plan, of a portion of the spray nozzle and reservoir attached thereto. Fig. 5 is a top plan, partly in section of the 50 detached clamping device by which the feed pipe of the spray nozzle is secured to a faucet of the bath tub. Fig. 6 is a transverse vertical sectional view through the

clamping device taken on line 6—6, Fig. 5. Fig. 7 is a vertical sectional view, partly in elevation of a modified form of spraying device, showing two spray nozzles with an interposed valve so as to permit the use of 60 both spraying nozzles or the lower one independently of the upper one.

The preferred form of shower bath attachment shown in Figs. 1 to 6 inclusive 65 comprises an upright pipe or conduit —1— composed of a plurality of sections —2— connected by screw couplings —3— so as to vary the height of the spray nozzle as —4— which is secured to the upper end of the 70 conduit —1—. The lower pipe section —2— is provided with a flexible extension —5— terminating in a coupling member —6— for slip connection with the nozzle of a faucet —7— as ordinarily used in connection with 75 a bath tub —A— although it is evident that it may be used in connection with any other faucet. The lower pipe section —2— is also provided with a hub or sleeve —8— rigidly secured thereto and formed with diametrically 80 opposite studs or trunnions —9— which are movably supported in guide-ways —10— of a clamping frame or yoke —11— adapted to be slipped from the underside around the neck of the faucet —7— where 85 it is clamped in position by an adjustable clamping member —12— also slidably mounted in the ways —10— and operated by means of a screw —13— through the medium of the sleeve —8—. This pipe-supporting sleeve —8— is, therefore, mounted 90 between the clamping member —12— and one end of the screw —13— and is adapted to be rocked to different angles upon its trunnions —9— for varying the angle of 95 discharge of the spray nozzle —4— and for this purpose the front and rear sides of the sleeve are provided respectively with a ribbed face —14— and a grooved face —15— both concentric with the axis of 100 movement of the sleeve, the rib —14— being guided in a groove —16— in the adjacent face of the clamping member —12— while the groove —15— serves to receive the adjacent end of the screw —13— to additionally 105 hold the sleeve against horizontal rocking movement.

The adjusting screw —13— is engaged in a threaded aperture —17— in the adjacent end of the yoke —11— and is disposed in 110 substantially the same horizontal plane as the clamping member —12— so as to effect

the horizontal adjustment of the sleeve —8— and clamping member —12— along the ways —10— in a plane parallel with said ways for clamping the pipe —1— to the faucet, it 5 being understood that the end of the yoke —11— opposite that in which the adjusting screw —13— is mounted is made circular or rounded outwardly, while the co-acting end of the clamping member —12— is concave. 10 to cause such parts to conform as nearly as possible to the circular contour of the portion of the faucet with which the clamping device is engaged. It is evident, however, that the pipe —1— may have a sliding connection 15 with the sleeve —8—, in which case, said pipe would be provided with an adjustable collar —18— normally resting upon the upper end of the sleeve and held in place by a set screw —19—, thus permitting the 20 clamping device to be adjusted vertically along the pipe relatively to the slip coupling —6—, to correspond to various lengths of faucet and also permitting the spray nozzle to be adjusted to different heights. 25 The spray nozzle —4— preferably consists of a laterally elongated pipe of rectangular cross section curved horizontally from end to end with its concave side facing the end of the bath tub opposite that at which 30 the faucet —7— is located and provided with a plurality of rows of relatively small apertures —20— arranged so as to project the water in jets converging toward the center of the arc of curvature of the nozzle or 35 within the area of the bath tub. The central portion of this spray nozzle is secured by brazing or otherwise to the upper end of the pipe —1— which is provided with an enlargement —21— forming a reservoir 40 communicating with the interior of said pipe for receiving a perfume, medicament or other toilet preparation which it may be desired to mix with the water as it is discharged through the spray nozzle. When 45 the upper end of the pipe is enlarged to form the reservoir —21—, the spray nozzle —4— is preferably secured in a recess in one side thereof near the bottom by brazing or otherwise, the portion of the spray nozzle 50 which extends through the enlargement —21— being provided in its upper and inner sides with a series of holes —22— to establish communication between the interior of the reservoir and nozzle —4—, said reservoir 55 being preferably provided with a removable screw cap —24— to permit it to be filled and refilled with medicament or other toilet substance when necessary.

In Fig. 7, I have shown a modified form of reservoir —21'— as having the upper end 60 of one side provided with a branch —26— to which is connected an upright pipe extension —27— carrying at its upper end an additional spray nozzle —4'— of substantially the same construction as the nozzle 65 —4— except that it is connected directly to the upper end of the pipe —27—, the latter being provided with a valve —28— located between the nozzles —4— and —4'— so that both of said nozzles may be used simultaneously when the valve is open or the lower one may be used independently of the upper one by simply closing the valve. When this modified form of spraying device is used, the reservoir —21'— may be secured directly 70 to the lower pipe section —2—, while the pipe section —27— may take the place of the superposed pipe sections shown in Figs. 2 and 3, thus permitting the simultaneous discharge of shower sprays from different elevations. 75

What I claim is:

1. A shower bath attachment for faucets comprising an upright sectional pipe having means for connection with the nozzle of a faucet, means for clamping the pipe to the main body of the faucet, said pipe having an enlarged portion forming a reservoir, a spray nozzle comprising a laterally elongated pipe section having its discharge 85 side concave and perforated substantially throughout its length, said spray nozzle secured to the reservoir portion of said pipe and having means of communication therewith for the passage of fluid. 90

2. A shower bath attachment for faucets comprising an upright pipe having means for connection with the nozzle of a faucet, means for clamping the pipe to the main body of the faucet, said pipe terminating in an enlarged portion forming a reservoir for a toilet substance, a spray nozzle comprising a laterally elongated pipe section having its discharge side perforated substantially throughout its length, said spray nozzle 100 having a portion lying within and secured to the reservoir portion of the pipe, and having means of communication therewith for the passage of fluid. 105

In witness whereof I have hereunto set my hand this 29th day of June, 1914.

CHARLES EDWARD SHAPLEY.
